UNITED STATES PATENT OFFICE

2,603,463

BRAKE CONTROL FOR TILTING
MIXING DRUMS

Robert Andrew Snyder, Gillette Heights, N. J., assignor to Worthington Pump and Machinery Corporation, Harrison, N. J., a corporation of Delaware

Application September 6, 1950, Serial No. 183,418

1 Claim. (Cl. 259—171)

1

This invention relates generally to concrete or similar type mixers having tiltable drums thereon, and more specifically to a brake means for combatting the tilting movement of said drum.

Mixers of the type above mentioned include generally a frame upon which is mounted a pivotable yoke member having a rotatable drum pivotally supported therein, with means provided for engaging and rotating the drum member, and tilting gears provided to swing or move the yoke in order to change the angular position of the drum mounted therein.

Under ordinary usage considerable looseness develops in the tilting gear which renders the drum dangerous in that it may without warning shift its load causing the drum to swing whereby it may injure the workmen operating the machine and/or lose a portion of the material being mixed therein.

In addition, it is sometimes advantageous to be able to hold the drum in one or more angular positions for the purpose of charging, mixing or cleaning the drum.

Accordingly, the present invention contemplates a control coating with the tilting gears, which includes brake means mounted about at least one of the tilting gears, which is operated by a lever, cam and spring action.

It is an object of the present invention to provide a control means for controlling the tilting movement of the drum on a cement or the like type mixer.

It is another object of the present invention to provide a control means for controlling the tilting movement of the drum or a cement or the like type mixer which includes means mounted about and coating with the tilting gear of the drum.

With these and other objects in view, as may appear from the accompanying specification, the invention consists of various features of construction and combination of parts, which will be first described in connection with the accompanying drawings, showing a brake control for tilting mixing drum, of a preferred form embodying the invention, and the features forming the invention will be specifically pointed out in the claim.

In the drawings:

Figure 1 is an end view of a typical mixer showing the invention thereon.

Figure 2 is a partial front view of a typical mixer showing the invention thereon.

Figure 3 is a section taken on the line 3—3 of Figure 2, showing the invention.

2

In the drawings the figures therein show the application of the invention to a cement or plaster type mixer, it being understood, however, that applicant does not intend to so limit the invention but that it is easily applicable to other similar type mixers.

Referring more particularly to the drawings, Figures 1 and 2 show a main frame assembly 1 including a base or axle member 2 in the horizontal plane and spaced uprights 3 and 4 in the vertical plane. The frame 1 is shown held in its desired position for operation by wheels 5 spring mounted on said axle member 2 and side supports 6 connected to the uprights 3 and 4. The mixer may be moved by pulling on the bail member 7 connected to the frame assembly which will tilt the machine to the vertical position allowing it to move freely on the wheels 5.

The spaced uprights 3 and 4 have split bearings 8 disposed at their upper ends to provide means for mounting a yoke member 9, as is shown in Figure 2 of the drawings.

Yoke member 9 is a substantially arcuate member having trunnions 10 on the outermost ends 25 of the arc, perpendicular to the center line thereof and extending laterally therefrom in axial alignment to provide means for mounting the yoke member 9 in the split bearings 8 disposed on the ends of the spaced uprights 3 and 4.

30 A mixing drum 11, substantially spherical in shape having a conical shaped charging and discharging opening at one end thereof, of which there are many well known types easily purchasable on the open market is adapted to be rotatably mounted as shown at 12 in the yoke member 9. The rotatable mounting 12 providing means for holding the mixing drum 11 in a vertical axis so that it may be rotated in a horizontal plane and allowing the mixing drum 11 to be tilted 40 from the vertical as the yoke member 9 is rotated on the trunnions 10, as hereinafter described.

The mixing drum 11 may be rotated by any suitable type of driving means, which includes a prime mover not shown, as it does not form a part of the present invention. The prime mover is mounted in a housing 13 connected to and supported by the upright 3. It is connected to a pinion gear 14 which in turn engages a ring gear 15 mounted about the outer circumference of the mixing drum 11. When the prime mover is in operation it rotates the pinion gear 14 which in turn drives the ring gear 15 causing the drum 11 connected thereto to rotate, all of which is clearly 55 shown in Figure 2 of the drawings.

Tilting gears

The means for tilting the mixing drum 11 operates directly on the yoke member 9. However, since the mixing drum 11 is movable with the yoke member 9 as the yoke member 9 is rotated back and forth the mixing drum 11 will move therewith.

Accordingly, Figures 1 and 2 show a tilt gear 16 located between the spaced upright 4 and the yoke 9 on the more easily accessible side of the yoke member. The tilt gear 16 is a substantially hollow cylindrical hub-like member with gear teeth 17 on the inner circumference thereof. One end of the tilt gear 16 is open and the other end is closed except for a bore of sufficient diameter to receive one of the trunnions 10 therethrough and to provide means for connecting the tilt gear 16 to the yoke 9 and a spur support 18 provided on the end thereof by suitable means such as bolts 19 whereby the tilt gear 16 when rotated as hereinafter described by the hand-wheel assembly will move or rotate the yoke member 9 on its trunnions 10.

The hand wheel assembly for operating the tilt gear 16 includes a bearing pin or shaft 20 fitted into a bearing and support structure 21 therefore which is mounted to extend through the spaced upright 4 by means of a flange 22 connected thereto and bolts 23 connecting the flange 22 to the spaced upright 4. The outer end of the shaft 20 is provided with suitable threaded and keying means whereby a hand wheel 24 can be fixedly connected thereto by means of a hand-wheel locking nut 25. The shaft 20 extends past the bearing and support structure 21 to lie inside tilt gear 16, in close proximity with the gear teeth 17 thereon, so that the teeth or connecting gear 26, fixedly connected to the inner end of shaft 20 and movable therewith will be in contact and mesh with the gear teeth 17 whenever the shaft 20 is rotated by means of the hand wheel 24. It being obvious that when the teeth mesh that tilt gear 16 will be rotated causing the yoke 9 to which it is fixedly connected to rotate back and forth therewith, in turn causing the mixing drum to tilt, all of which is clearly shown by Figures 1 and 2 of the drawings.

Braking means to control the tilt gear 16

Rotation of the yoke 9 will control the tilting of the mixing drum 11. However, as above described, rotation of the yoke 9 is controlled by the tilt gear 16 which is in turn operated by the hand wheel assembly. In order to control the angular movement or position of the tilt gear 16, a braking means is provided therefor.

Figures 1 and 2 show brake band 27 as a substantially circular band-like member open at one point to form outwardly extending ears 28 and 29. Brake band 27 is held free or loosely mounted on the outer circumference of the tilt gear 16, and connected to the brake band for controlled contact with said outer circumference as hereinafter described in any suitable type of brake lining material 30, of which there are many well known types easily purchasable on the open market. It is understood that while the present invention shows the outer circumference of the tilt gear 16 as being substantially smooth, that the surface may be adapted to receive suitable material or be changed whereby the frictional contact with the brake lining material 30 may be increased or decreased as conditions may require.

The brake band 27 is shown as mounted about the tilt gear 16 so that the opening thereof is disposed below the tilt gear 16 and the outwardly extending ears 28 and 29 extend downwardly to receive the brake band control means hereinafter described therethrough. A V-shaped bracket 31 is shown mounted on the outer surface of the brake band 27 substantially opposite to the opening thereon, the arm directed to extend downwardly to abut the tilt gear 16 when the brake band is in operation to prevent the brake band from slipping off of the tilt gear in the lateral direction. It is understood that while this type of bracket means to prevent slipping of the brake band is shown that other means embodying the same idea may be utilized for this purpose.

Figure 3 shows the ears 28 and 29 extending downwardly so that ear 28 will be adjacent operating shaft bracket 32 mounted on a lateral extension 33 formed on the spaced upright 3, and openings provided on the ears 28 and 29, respectively, will be in alignment with each other and with an opening 34 on the operating shaft bracket 32.

Operating shaft 35 to operate the brake band 27 is an elongated member having a cylindrical ring-shaped cam following member 36 at one end in the axial line of the shaft. The other end of the operating shaft 35 is threaded which allows the shaft to be slidably mounted in the opening 34 of the operating shaft bracket 32 and to pass through the openings in alignment therewith in the ears 28 and 29 where it will be threadably connected outwardly thereof to an adjusting nut 37. In order to hold the adjusting nut in its desired position a washer member 38 and a locking nut 39 are provided therefor.

The brake band will be held free or loosely about the tilt gear 16 by a separating spring 40 mounted about the operating shaft 35 between the ears 28 and 29 which normally in tension will abut and hold open the ears 28 and 29 and, in addition, force them open whenever the spring is released during operation of the operating shaft 35 as hereinafter described.

The ring-shaped cam following member 36 on the operating shaft 35 provides means for moving the operating shaft in a lateral direction. Thus Figure 3 shows a cylindrically-shaped cam member 41 rotatably mounted in said ring shaped cam following member 36 having an eccentric bore 42 therein. Cam 41 provides an operative connection between said operating shaft 35 and a manually operated L-shaped cam lever 43 which is fixedly connected in said eccentric bore 42 by means of a set screw 44. The cam lever 43 is pivotally mounted in the cam lever support 45 formed on the lateral extension 33 so that one leg of the L-shaped portion extends downwardly.

In operation, the cam lever 43 is grasped manually and pushed causing the cam 41 to rotate inside the cam following member 36. However, since the cam 41 has an eccentric bore 42 therein as it rotates it will move the cam follower 36 in the lateral direction along a substantially horizontal plane. Since, however, the operating shaft 35 is fixedly connected thereto it will move laterally causing the adjusting nut 37 and washer 38 to abut and move the ear 29 towards the ear 28 which is prevented from moving as it abuts the operating shaft bracket 32. Thus, separating spring 40 will be compressed and the brake band 27 will be tightened about

the tilt gear 16 which will prevent the tilt gear 16 from rotating further. When the lever member 43 is released the separating spring 40 will expand separating the ears 28 and 29 releasing the frictional engagement between the tilt gear and the lining 30 in the brake band. The amount of pressure exerted by the brake band 27 is a function of the manual pressure exerted on the cam lever 43.

It appears obvious that if it is desired to hold the mixing drum 11 in any desired angular position that the tilt gear 16 will be manually adjusted by operating the hand wheel 24 until the yoke 9 and mixing drum 11 are moved to the desired angle, and that sufficient manual pressure exerted thereafter on the cam lever 43 will hold the drum 11 in this position because the tilt gear 16 will be prevented from rotating in either direction until the lever 43 is released.

While it is not shown, it is believed to be a mere mechanical expedient to provide means for locking the manually operated cam lever when it is desired to hold the drum at some given angular position, for example a notched plate into which the cam lever 43 may be seated.

While one form of the invention has been illustrated and described, it will be understood that the invention is not to be limited to the

specific construction and arrangement of parts shown, but that they may be widely modified within the invention defined by the claim.

What is claimed is:

5 In a mixer, a supporting structure, a drum-carrying yoke, trunnions on said yoke and engaging said supporting structure for pivotally supporting the yoke, an internally toothed tilting gear mounted on one of said trunnions, a
10 brake band about the periphery of said tilting gear, said brake band being split and having a pair of radial ears thereon, means for anchoring one of said ears, a rod connected to the unanchored ear, an eccentric connected to said rod, and a lever connected to the eccentric for rotating the eccentric to move said unanchored ear for tightening or loosening said brake band.

15 ROBERT ANDREW SNYDER.
